UNITED STATES PATENT OFFICE

JOHN DEWRANCE, OF SOUTHWARK, LONDON, ENGLAND

AUTOMATIC REGULATING VALVE

Application filed March 19, 1929, Serial No. 348,211, and in Great Britain May 5, 1928.

The present invention relates to automatic regulating valves applicable, for example, as reducing valves or for the control of the supply of fluid in accordance with pressure variation.

A regulating valve in accordance with this invention comprises a main valve adapted to be opened by a spring or its equivalent, acting in opposition to a fluid pressure under control of a pilot valve essentially similar in its action to the main valve, but provided with a balancing device.

In order that the invention may be clearly understood and readily carried into effect, it will now be described more fully with reference to the accompanying drawing, which illustrates, by way of example, two forms of valve in accordance with the invention and in which:—

20 Figure 1 is a longitudinal section of the main valve,

Figure 2 shows the main valve in side view and the pilot valve in longitudinal section,

Figure 3 is a plan view of the main and pilot valves and

Figure 4 depicts a modified form of pilot valve in longitudinal section.

In applying the invention to a reducing valve as shown in Figures 1, 2, and 3, the main valve may be constituted by an ordinary lift valve 1 arranged to pass fluid from the high-pressure inlet 2 to the low-pressure outlet 3 and adapted to be opened by a spring 4, preferably adjustable as indicated, and to be closed by fluid pressure acting on an operative diaphragm 5 or the like in opposition to the spring 4. The pilot valve may consist of a similar structure, with the addition, however, of a second diaphragm 6 or

40 the like arranged to balance the action of fluid pressure on the disc or the like constituting the lift valve 7. Fluid from the high-pressure supply is admitted, through a duct 8 and an adjustable needle or like valve 9, to the space 10 in the pilot valve between the lift valve 7 and its balancing diaphragm 6 and from there passes by a passage 11 to the space 12 in the main valve where it is free to act on the operative diaphragm 5 of

45 the latter. The operative diaphragm 13 of

the pilot valve is, however, acted upon by the low-pressure fluid, a suitable connection 14 from the low-pressure outlet 3 being made for this purpose by a branch 15, this connection also passes steam from the valve 7 to the low pressure side. In their normal position both the main and pilot valves 1 and 7 are open due to the action of their springs 4 and 16, but on high-pressure fluid being admitted the main valve 1 is closed by pressure acting on the diaphragm 5 to an extent sufficient to produce the desired reduced pressure on the low-pressure side. Correspondingly the pilot valve 7 is also partially closed owing to the action of the reduced pressure on its operative diaphragm 13. If now the reduced pressure should fall, owing, for example, to increased rate of consumption, the pilot valve 7, due to reduction of pressure on the diaphragm 13, is opened slightly by the spring 16, thus permitting escape of high-pressure fluid through the pilot valve 7 at a greater rate than can be supplied through the needle valve 9 and so reducing the pressure acting on the diaphragm 5 of the main valve 1, the opening of which is thereby increased, thus resulting in restoration of the required pressure on the low-pressure side. Conversely, should this low-pressure increase an action opposite to that above described occurs, whereby the aperture of the main valve 1 is reduced and the pressure on the low-pressure side is brought back to its normal valve.

Obviously instead of or in combination with any or all of the diaphragms employed in the main and pilot valves pistons may be used. Thus in the pilot valve depicted in Figure 4, the balancing diaphragm 6 is replaced by a piston 18. This figure also shows a construction suited particularly in applying the valve to the control of the steam supply to a water-heating boiler in which the steam is passed through a pipe immersed in the water to be heated. In this case it is not a question of reducing the steam pressure, and hence the steam supply is connected to the inlet 2, while the space above the water, the pressure in which will vary in accordance with the temperature to which the water is

raised, is connected to the space 17 in the pilot valve situated in proximity to its operative diaphragm 13. By means of an inlet aperture 19, the passages 14 and 15 are dispensed with and the space above the valve 7 is open to atmosphere through an aperture 20. Thus the rate of steam supply is automatically controlled in accordance with the pressure existing above the water in the boiler, that is to say, in accordance with the temperature in the boiler.

What I claim and desire to secure by Letters Patent of the United States is:

1. A regulating valve comprising in combination a main valve, a spring acting on said main valve in opposition to the direction of fluid pressure which it is intended to apply thereto, a pilot valve and spring similar to said main valve and spring and a balancing device for said pilot valve.
2. A regulating valve comprising in combination a main valve, a spring acting on said main valve in opposition to the direction of fluid pressure which it is intended to apply thereto, an operative diaphragm associated with said main valve, a pilot valve and spring similar to said main valve and spring, a balancing device for said pilot valve, and a needle valve associated with said pilot valve and adapted to admit fluid pressure to said balancing device.
3. A regulating valve as in claim 2, in which the needle valve serves to admit fluid from the high-pressure side of the main valve to a space communicating both with the pilot valve and with its balancing device and also to the operative diaphragm in the main valve.
4. A regulating valve as in claim 2, in which the pilot valve serves to by-pass fluid admitted by the needle valve at a rate which causes variation in the pressure acting on the operative diaphragm of the main valve in accordance with the pressure at the outlet of the main valve.
5. A regulating valve as in claim 1, in which the balancing device of the pilot valve is constituted by a diaphragm.
6. A regulating valve as in claim 2, in which the pilot valve is fitted with an operative diaphragm and means is provided for admitting fluid from the low-pressure side of the main valve to said operative diaphragm.

JOHN DEWRANCE.
